UNITED STATES PATENT OFFICE.

ANDREW N. LAWRENCE, OF LOS ANGELES, CALIFORNIA.

SHOW-CASE.

No. 879,655.

Specification of Letters Patent.

Patented Feb. 18, 1908.

Application filed April 18, 1907. Serial No. 369,173.

To all whom it may concern:

Be it known that I, ANDREW N. LAWRENCE, of the city of Los Angeles, in the county of Los Angeles, in the State of California, have invented certain new and useful Improvements in Show-Cases, of which the following is a full, clear, and exact specification, reference being had to the accompanying drawings, and to the figures and reference-numerals marked thereon.

My said invention relates to that class of show cases, wherein swinging shelves are suspended from horizontal rods, the extremities of which rods are pivoted in socket bearings attached to endless chain belts, said chain belts being rotated by means of sprocket wheels driven by suitable mechanism.

The principal object of my said invention is to provide a show case wherein the shelves can be continuously rotated in the interior of the case, thereby thoroughly exhibiting the display of merchandise contained therein, and is particularly adapted for use in stores, offices, libraries, and residences, or other places where show cases are used.

Another object of my said invention is to provide a show case adapted to the display and exhibition of various classes of merchandise, so constructed and arranged that convenient access is had to the contents thereof at all times.

The chief advantage of a show case of this nature, is the large capacity of display in comparison with the small amount of space required. Another advantage being the effective display obtained in attracting attention by the use of motion.

I accomplish these objects by means of the device hereinafter described, and shown in the accompanying drawings, wherein;

Figure 1, is a front elevation of my new or improved show case, with a portion of the front casing removed. Fig. 2, is an end elevation of Fig. 1. Fig. 3, is a cross section on the line *a*, *a*, Fig. 1. Fig. 4, is an enlarged view in perspective of a portion of one of the endless chain belts, showing socket bearings attached thereto. Fig. 5, is another view of the socket bearing. Fig. 6, is a view in perspective of a portion of a shelf and suspension rod, with triangular hanger attached thereto. Fig. 7, is a front elevation of an adjustable brace. Fig. 8, is a detailed view in elevation of one of the interior rotating sprocket wheels. Fig. 9, is a section on the line *b*, *b*, Fig. 8, showing journals as used with

both interior and exterior rotating sprocket wheels. Fig. 10, is a similar section as Fig. 9, where only an interior rotating sprocket wheel is required. Fig. 11, is a sectional view on the line *c*, *c*, Fig. 9, and parallel to the plane of Fig. 8.

In Figs. 1, 2, and 3, the body portion of my show case is marked 1, the end portions 2, the base 3, and the side casings 4. The side casings 4, form frames for the panels 5, which may be of glass or other suitable material. The ends 2, base 3, and side casings 4, may be constructed of wood or metal. The top 6, of wood, glass, or other suitable material, forms a covering for the case 1, and may be attached to the ends 2, and side casings 4, in any desired manner. Drop doors 7, and 7', as shown in Figs. 1, and 3, are fitted in the side casings 4, to give access to the interior of the show case 1. These drop doors 7, and 7', are provided with hinges 8, affixed to the lower edges thereof, and secured to the side casings 4, so that the drop doors 7, and 7', may swing out and downwardly as shown in dotted lines in Fig. 3.

Slide braces 9, of any desired style, are affixed to the drop doors 7, and 7', and the side casings 4, for the purpose of retaining the door in a horizontal position when open, thereby forming a shelf or display counter.

A catch 10, is used to fasten the doors 7, and 7', when closed. Display shelves 11, are rigidly secured at both ends, to the base of triangular hangers 12, which are pivotally suspended from horizontal rods 13, extending longitudinally in the interior of the case 1. The extremities of the rods 13, are pivotally mounted in socket bearings 14, which are attached to the endless chain-belts 15, and 15', by means of bolts 16, as shown in Figs. 4, and 5. The endless chain-belts 15, and 15', are carried by sprocket wheels 17, and 17', rigidly mounted on journals 18, and 18', and placed on the inner side of the end portions 2. The journals 18, and 18', pass through journal bearings 19, from the interior of the case 1, and are retained in position therein by means of lock nuts 20, as shown in Figs. 10, excepting where journals 18', are fitted with exterior sprocket wheels 21, and 21', as shown in Figs. 1, 2, and 9. The journal bearings 19, are inserted in the end portions 2, of the case 1, and are secured in place by means of plates 22, and 22', fastened to end portions 2, by means of screws 23. Adjustable braces 24, are placed over

100

105

110

the plates 22, on the interior face of the end portions 2, of the case 1, and firmly secured thereto by means of bolts 25, for the purpose of adjusting and supporting the journal bearings 19, as shown in Figs. 3, and 8.

Endless chain belts 26, and 26', connect sprocket wheels 21, and 21', with sprocket wheels 27, and 27', respectively. The sprocket wheels 27, and 27', are rigidly mounted on the extremities of a horizontal shaft 28, which extends longitudinally through the lower portion of the case 1, and parallel to the bottom thereof. Said shaft 28, passes through anti-friction bearings 29, and 29', inserted in the end portions 2, of the case 1, as shown in Fig. 1, and is supported near the center of its length by means of a bearing 30. On the shaft 28, is rigidly mounted a sprocket wheel 21, which is geared to a sprocket chain 32, passing down through an aperture 32', in the base 3, and connected to any suitable power for the operation thereof.

A sub-casing 33, may be attached to the end portions 2, of the case 1, as shown in dotted lines in Fig. 1, for the purpose of inclosing and protecting the exterior mechanism.

When power is applied to the sprocket chain 32, motion is transmitted through the sprocket wheel 31, to the shaft 28, thereby rotating the sprocket wheels 27, and 27', carrying the endless chain belts 26, and 26', in the direction indicated by the arrows in Figs. 2, and 3, thereby causing the sprocket wheels 21, and 21', to revolve and transmit motion through the journal 18, to the sprocket wheels 17', on the interior of the case 1. The revolving of the sprocket wheels 17', cause the endless chains 15, and 15', to rotate in the direction indicated by the arrows in Figs. 2, and 3. It will be seen by this operation, that as the endless chain belts 15, are rotated around the sprocket wheels 17, and 17', as particularly shown in Fig. 3, the socket bearings 14, carry the rods 13, and the swinging shelves 11, up to and across the top, and down to and across the bottom of the interior of the case 1, thereby causing a continuous rotation of the swinging shelves 11. The swinging shelves 11, being hung loosely upon the bars 13, by means of the hangers 12, the bars 13, being pivotally suspended from the endless chain belts 15, and 15', the shelves 11, are caused to be rotated in a horizontal position by means of their weight.

It is to be understood that the direction of rotation may be reversed if desired.

I claim as my invention:

1. In a show case, the combination of a suitable case, a plurality of shelves suspended from rods by hangers, socket bearings in which said rods are pivotally mounted, endless chain belts upon which said socket bearings are carried, sprocket wheels mounted on journals and adapted to support said chain belts, anti-friction bearings to receive said journals, metallic plates retaining said bearings in position and adjustable angular braces made in two sections, pivoted at the vertex and adapted to support and adjust the before mentioned journals, substantially as described.

2. In a show case, the combination of a suitable case, a plurality of shelves suspended from rods by hangers, socket bearings in which the extremities of said rods are pivotally mounted, endless chain belts upon which said socket bearings are carried, sprocket wheels rigidly mounted on journals and adapted to support said chain belts, means for adjusting said journals journal boxes fitted with anti-friction rollers in which the before mentioned journals are carried, two of said journals extending through said journal boxes and provided with sprocket wheels rigidly mounted on the extremities thereof, two endless chain belts carried upon the last named sprocket wheels, an equalizing shaft extending longitudinally across and near the bottom of the case, having both extremities projecting through the ends thereof, anti-friction bearings in which said shaft is mounted, sprocket wheels rigidly mounted on the extremities of said shaft adapted to operate the last named endless chain belts, and a sprocket wheel mounted near the center of said equalizing shaft with means to connect with a suitable driving power for rotating the same, all operating in the manner and for the purposes substantially as hereinbefore described.

In testimony whereof, I have hereunto set my hand and seal at the city of Los Angeles aforesaid, in the presence of two subscribing witnesses.

ANDREW N. LAWRENCE. [L. S.]
